PROPELLER HUB STRUCTURE

Erle Martin, West Hartford, and Raymond P. Lambeck, Manchester, Conn., assignors to United Aircraft Corporation, East Hartford, Conn., a corporation of Delaware

Application December 28, 1953, Serial No. 400,738

12 Claims. (Cl. 170—160.32)

This invention relates to hydraulically actuated aeronautical propellers and particularly to means for lubricating the blade mechanism without subjecting the propeller hub to excessive pressures.

An object of this invention is a hydraulically actuated propeller having only two fluid lines leading to the propeller and utilizing the pitch changing operating fluid for lubrication of the blade bearings and pitch change gears in the interior of the hub in which means are provided preventing the application of the full operating pressure to the hub interior.

A further object of the invention is a hydraulic propeller in which the hub interior is sealed from the double-acting pitch changing motor and valve mechanism is provided for automatically connecting the inoperative side of the double-acting pitch changing motor with the hub interior.

A still further object is the provision of a shuttle valve actuated by the pitch changing motor actuating fluid for blocking the motor actuating fluid from the hub interior and connecting the inoperative side of the motor with the hub interior.

Other and additional objects will be apparent from the following specification and the accompanying drawings in which:

Fig. 1 is a side elevation with parts broken away, showing a propeller with the lubricating shuttle valve.

Fig. 2 is an enlarged view of the pressure actuated shuttle valve of Fig. 1.

Fig. 3 is a section in line 3—3 of Fig. 2.

Fig. 4 is a view similar to Fig. 2 but showing the valve in its other position.

In hydraulically actuated aeronautical propellers it has been customary to lubricate the blade retaining bearings and the blade drive gears by the hydraulic fluid used to actuate the pitch changing motor. In small sizes and when the actuating fluid does not reach very high pressures, it has been possible to make barrels which could stand the fluid pressure and it has been possible to seal the barrels so that no material leakage would take place. However, with the advent of larger barrels and higher operating pressures it has been found that the sealing problem becomes acute and the barrels cannot be properly sealed to retain the full operating pressure applied to the hydraulic pitch changing motors. In addition the high oil pressure in the hub barrel places an additional load on the barrel structure which can be avoided by the use of the lower pressures.

The present invention relates to mechanism for utilizing the hydraulic pitch changing fluid of a double-acting pitch changing motor for lubricating the blade bearings and drive mechanism but preventing the application of the high pressure fluid to the interior of the barrel. In order to accomplish this the hub or barrel has been sealed off from the pitch changing motor and a separate lubricating line led from the motor feed lines to the barrel interior. A valve actuated by the pressure of the pitch changing fluid is inserted in the line leading to the

2

interior of the barrel and is actuated by the pitch changing fluid to block pitch changing fluid from the barrel interior and simultaneously connect the barrel interior with the drain or low pressure side of the pitch changing motor.

In the propeller structure shown in the drawing, which is a well-known propeller construction, such as is shown in Patents Nos. 2,280,713 and 2,280,714 and is chosen for the purpose of illustrating the invention. As this type of propeller is now well known it will be very briefly described, further details may be obtained from the cited patents. A propeller indicated generally at 10 mounted on a shaft 12 is driven by an engine 14. The propeller has a hub or barrel 16 supporting blades 18 and 20 on retaining bearings 22 and is driven by a spider 24 having arms 26 extending into the blade interior and mounted on the propeller shaft 12 and driven by splines 28. A dome 30 is secured to the outboard side of the barrel 16 and acts as a cylinder for the pitch changing piston 32 which carries the cam follower 34 through oppositely directed cam slots 36 and 38 in the stationary cam sleeve 40 and the movable cam sleeve 42, respectively. Movable cam sleeve 42 carries bevel gear 46 at one end thereof which gear meshes with gears 48 on the several blade ends. Reciprocating movement of the piston 32 in the cylinder 30 will rotate cam sleeve 42 and thus rotate blades 18 and 20 to change their pitch. A tube 50 is led through the center of the piston for conducting actuating fluid from the propeller shaft 12 to the front side or outboard side of the piston. A packing 52 seals the piston 32 with respect to the cylinder 30 and a packing 54 seals the piston 32 with respect to the tube 50.

A valve housing 56 having fluid distributing passages therein is threaded into the interior of propeller shaft 12 and seats on a gasket 58 against the closed end 60 of a pair of sleeves, 62, 64 fixed in the propeller shaft 12 and forming an annular fluid passage 66 surrounding a central fluid passage 68. The interior of the hub 16 is sealed from the inboard end of the piston 32 and the open end of cylinder 30 by a series of packings or seals including a seal 70 between the barrel 16 and the inboard end of cylinder 30, a seal 72 between the inboard end of cylinder 30 and the stationary cam sleeve 40, a seal 74 between the stationary and rotatable cam sleeves 40 and 42 and a seal 76 between retaining nut 78 and a sleeve 80 secured in fluid tight relation to the movable cam sleeve 42 and a seal 82 between the retaining nut 78 and the valve housing 56. The packing 58 seals the inboard end of valve housing 56 from the interior of propeller shaft 12 at the interior of the propeller hub. The propeller hub interior is thus sealed from the pitch changing motor so that fluid applied to the rear of the double-acting motor does not find a ready access to the hub interior.

Fluid is fed to the pitch changing motor from the engine lubricating system comprising an engine oil reservoir and the engine lubricating pump 84 having the usual relief valve 86 for maintaining a limited pressure on the lubricating fluid. Engine oil is led through the conduit 88 to a double-acting governor 90 which may be of any well-known type such as is shown in Patent No. 2,402,065. This type of governor is now well-known and will be only briefly described here, further details may be obtained from the cited patent. This governor includes the usual flyweights 92 acting against a spring 94 for moving a pilot valve 96 in overspeed conditions to connect line 98 with the high pressure output of pump 100 appearing in chamber 102, and the line 104 with engine oil pressure appearing in line 88 which is also the inlet to pump 100. The governor acts to substantially block fluid flow for onspeed conditions and in underspeed conditions connects line 104 with the high pressure out-

put of pump 100 and line 98 with the engine oil pressure occurring in conduit 88. The governor is supported in a well known manner outside of the propeller hub, as on a pad on engine 14 and is driven in the usual manner from the engine 14 by the gear 106. Line 98 from the governor is connected in a well-known manner through transfer rings, not shown, with the fluid passage 66 rotatable with propeller shaft 12. Line 104 is connected in a similar, well-known manner through transfer rings, not shown, with fluid passage 68 rotatable with, and located in the interior of, the propeller shaft 12. These two passages 66 and 68 are the only fluid lines leading to the propeller. Passage 68 leads into chamber 108 in valve housing 56 which is connected by a drilled passage 110 with the area at the inboard side of piston 32. Passage 66 is connected through orifice 112 with passage 114 and through orifice 116 in the valve cage 118 to the interior of the valve cage and from thence to the interior of tube 50 leading to the outboard side of the pitch changing piston 32. Hence it will be seen that in one extreme position of the governor pilot valve, fluid under engine oil pressure is maintained on one side of the piston and fluid under high pressure is led to the other side of the piston to move the piston in one direction and in the other extreme position of the governor pilot valve these pressures are reversed in their application to the piston to move the piston in the other direction thus giving the double action to the governor and to the motor. The interior of the barrel is open to groove 120 which groove is blocked from passage 114 by plug 122 and is connected by passage 124 with groove 126 in valve cage 118. Valve cage 118 is fixed in valve housing 56 and the groove 126 is sealed from both the chamber 108 and the passages 114. Seals are also provided at the opposite end of the valve cage 118 sealing its connection with the tube 50 and the joint between the valve cage and the valve housing 56. A valve 128 having a stem 130 movable in a bore 132 in valve cage 118 is urged by spring 134 onto a seat 136 in the valve cage 118. One end of spring 130 rests on the valve cage 118 and the other end rests on a washer 138 secured against outward movement by a pin 140. Groove 126 is connected by a passage 142 with a chamber 144 under the seat of valve 128. The stem 130 of the valve 128 has one side flattened to provide a passage 146 connecting chamber 144 with chamber 148 at the inboard end of the valve cage as shown in Fig. 2. From the above description it will be apparent that one side of the piston is always connected through tube 50 to one side of valve 128 and the other side of the piston is always connected through passage 110 to chamber 108 and the other side of the valve 128. Valve 128 is moved by a predominance of pressure on one side or the other so as to seat valve 128 on seat 136 as shown in Fig. 2 or to move the valve to the left until washer 138 contacts the flat surface on the inboard side of valve cage 118 as shown in Fig. 4.

As shown in the drawings, with valve 128 seated on seat 136 the interior of the barrel is connected through line 124, groove 126, passage 142, chamber 144, passage 146, chamber 148, and chamber 108 with the fluid passage 68 and the governor outlet 104 which, in the overspeed conditions as shown, is connected with line 88 containing fluid under engine oil pressure. Hence when fluid under pitch changing pressure is applied to the outboard side of piston 32, the interior of the barrel and the rear of the piston are connected with engine oil pressure.

When an underspeed condition occurs and the pitch is to be reduced, the pilot valve 96, Fig. 1, will move downwardly connecting the line 104 with high pressure and the line 98 with engine oil pressure. High pressure in line 104 is led through passage 68 to the inboard side of valve 128 forcing it to the left until washer 138 contacts the inboard side of valve cage 118 as shown in Fig. 4. The inboard end 150 of the flattened portion of stem 130 will thus be within bore 132. Passage 146 will

be blocked, thus sealing the chamber 144 of the valve cage from chamber 148 and the high pressure which is led through passage 110 to the inboard side of the piston 32. As previously indicated, this area at the inboard side of piston 32 is sealed from the interior of the barrel. Movement of the valve 128 to the left will move valve 128 off of the seat 136 thus opening the chamber 144 to passages 114. The interior of the barrel is then connected through passages 124, groove 126, passages 142, and chamber 144 with orifices 116 and passages 114 which connect with the fluid passage 66 in the propeller shaft which is connected through line 98 with the engine oil pressure. Thus although high pressure is applied to the rear of piston 32, this high pressure is sealed from the interior of the barrel and the pressure on the interior of the barrel is limited to the engine oil pressure.

The above described structure provides a propeller having a double-acting hydraulic motor changing the propeller pitch with only two fluid lines leading to the propeller and a valve mechanism actuated by the pressure of the pitch changing fluid for blocking that fluid from the barrel interior and simultaneously connecting the barrel interior with the drain side of the pitch changing motor. Although we have described this invention as applied to a spider and split barrel type of propeller it is within the scope of the invention to apply it to other types of propellers such as the single piece barrel type shown in Patents Nos. 2,653,668 and 2,477,868.

While there has been described and illustrated a mechanical embodiment of what is now considered to be the preferred form of the invention, it is to be understood that the invention is not limited to the construction so illustrated and described, but that such changes in size, shape and arrangement of parts may be resorted to as come within the scope of the subjoined claims.

We claim:

1. In an aeronautical propeller having blades and a hub and a double-acting hydraulic pitch-changing motor carried by said hub and having interchangeable high and low pressure sides, means sealing the interior of said hub from said motor, a pair of fluid lines, one line connected with one side of said motor and the other line connected with the other side of said motor, control mechanism outside said hub and held against rotation with said hub and connected with both said lines and movable to direct fluid to said lines to interchange said high and low pressure sides, a valve carried by said hub, connected with both said lines and with the hub interior and means operative responsive to movement of said control mechanism for operating said valve to connect said hub interior with said low pressure side.
2. A device as claimed in claim 1 in which said control mechanism includes means connecting one side of said motor with hydraulic fluid under a predetermined pressure and the opposite side with hydraulic fluid under a higher pressure, and means for reversing said connections.
3. A device as claimed in claim 2 in which the hydraulic fluid is lubricating oil and in which the predetermined pressure is a substantially constant pressure.
4. A device as claimed in claim 2 in which the propeller is driven by an engine having a lubricating system and in which the hydraulic fluid is engine lubricating oil and the predetermined pressure is the engine lubricating system pressure.
5. In an aeronautical propeller having blades and a hub and a double-acting hydraulic pitch-changing motor carried by said hub and having interchangeable high and low pressure sides, means sealing the interior of said hub from said motor, a pair of fluid lines, one line connected with one side of said motor and the other line connected with the other side of said motor, control mechanism outside said hub and held against rotation with said hub and connected with both said lines and movable to direct fluid to said lines to interchange said high and low pressure sides, a valve carried by said hub, connected with

both said lines and with the hub interior and means actuated by the fluid pressure in one line for moving said valve to connect the other line with the hub interior and actuated by the pressure in said other line to move said valve to connect said one line with the hub interior as the low pressure changes from one side of said motor to the other. 5

6. A device as claimed in claim 5 in which said valve is a pressure actuated shuttle valve.

7. A propeller including a hub, blades mounted on 10 bearings for pitch changing movement in said hub, a double-acting pitch changing motor connected with said blades, means for supplying fluid under pressure to said motor for moving the same to change the propeller pitch, a control valve for changing the application of pressure from one side to the other of said motor to change the direction of movement of said motor and a second valve, hydraulically connected with both sides of said motor, and having a connection with the interior of said hub, and actuated by said fluid pressure to automatically connect the interior of said hub with the side of said motor opposite to that receiving said fluid pressure to supply fluid to the interior of said hub and prevent the application of fluid at motor operating pressure to the interior of said hub. 20

8. A propeller including a hollow hub, a cylinder having a closed end and an open end and secured at the open end to said hub, blades supported on bearings in said hollow hub, a piston in said cylinder mechanically connected with said blades for changing their pitch, 30 means selectively supplying fluid under pressure to one side or the other of said piston to increase or decrease the blade pitch, means, including a valve cage, sealing the hub interior from said cylinder open end, two fluid lines leading to said propeller, means permanently connecting one line with one side of said piston and the other line with the other side of said piston, valve means in said valve cage connected with said lines, said valve having a valve controlled connection between said lines and the interior of said hub and movable by a predominance of pressure in either line to block that line from the hub interior and connect the other line with the hub interior. 35

9. In an aeronautical propeller having blades and a hub and a double-acting hydraulic pitch changing motor carried by said hub, means sealing the interior of said hub from said motor, a pair of fluid lines leading to said 40

propeller, one line connected with one side of said motor and the other line connected with the other side of said motor and a pressure actuated shuttle valve having one side connected with one fluid line and the other side connected with the other fluid line and having a line controlled by said valve connecting the valve with the interior of said hub for connecting the interior of said hub with the low pressure side of said motor.

10. In an aeronautical propeller having blades and a hub and a double-acting pitch-changing motor carried by said hub and having interchangeable high and low pressure sides, means sealing the interior of said hub from said motor, a hydraulic control valve for said motor operable to selectively interchange the motor high and low pressure sides, a pair of fluid lines connecting said hydraulic control valve with opposite sides of said motor, and a second valve connected with both said lines between said control valve and said motor automatically connecting the interior of said hub with the line leading to the low pressure side of said motor.

11. A device as claimed in claim 10, including means, actuated by the motor actuating pressure, moving said second valve to change the connection to the hub interior from one line to the other as the low pressure changes from one side of the motor to the other. 25

12. In an aeronautical propeller having blades and a hub and a double-acting hydraulic pitch changing motor carried by said hub, means sealing the interior of said hub from said motor, a valve connected with the hub interior and both sides of said motor and connecting the interior of said hub with the low pressure side of said motor and means actuated by the motor actuating pressure moving said valve to change the connection to the hub interior from one side of said motor to the other as the low pressure changes from one side of said motor to the other. 30
